UNITED STATES PATENT OFFICE.

SHUBAEL COTTLER, OF NEW YORK, N. Y.

DIE FOR MAKING BRACELETS.

SPECIFICATION forming part of Letters Patent No. 237,823, dated February 15, 1881.

Application filed June 11, 1880. (No model.)

To all whom it may concern:

Be it known that I, SHUBAEL COTTLER, of the city, county, and State of New York, have invented a new and Improved Die for the Manufacture of Bracelets; and I do hereby declare that the following is a full, clear, and exact description of the same.

The methods heretofore pursued in the manufacture of fine band or parallel-sided gold bracelets involve so much care, skill, and time that their cost is high relative to the value of the metal entering into their structure and as compared with most other articles of gold jewelry. The desired perfection of construction and finish is, moreover, rarely attained, the semicircular parts of the bracelet tending to buckle or become otherwise distorted and irregular in shape while being burnished and otherwise manipulated in the process of manufacture, so that in the final finishing operation there are high parts that require to be taken off or cut away, which reduces the thickness of the metal unequally and impairs the strength, durability, and value of the completed article.

By use of a die constructed as hereinafter described I am enabled to produce band bracelets at less cost than heretofore, and with superior finish, strength, durability, and regularity of form.

In accompanying drawings, Figures 1 and 2 are respectively a perspective and sectional view of a half band or bracelet having the form in which it comes from the die shown in Figs. 6 and 7. Fig. 3 represents in perspective a tube from which a half-band is made and a mandrel inserted therein for the purpose of giving it the required shape preliminary to the operation of the die thereon. Fig. 6 is a vertical section, on line $x-x$, Fig. 7, of the die for shaping the half-band, the plunger being shown (in full lines) forced into the matrix or lower part of the die and resting on the half-band, which is compressed between them. Fig. 7 is a plan view of the matrix or receiving-die.

I form each half of a band bracelet, Figs. 1, 2, from a tube which is either seamed or seamless, according to the desired quality of the article or the requirements of the trade. The first step necessary to produce the seamed tube is to form it from a plate by drawing the latter into the shape of a straight cylinder and then soldering its opposite edges in the usual

way. Such cylinder or round tube is then drawn several times through drawing-dies and gradually reduced to the desired form in 55 cross-section, which, as represented in Fig. 3, is that of the ordinary band bracelet. Previous to the last draw, however, a square-edged mandrel, Y, is inserted in the straight tube to prevent buckling or other distortion of the 60 parallel sides by the compressive action of the dies.

It will be observed that the seam is in the middle of one of the broad sides, Fig. 4, in place of being contiguous to the narrow sides, 65 as usual.

Having thus obtained a tube, X, of the required form, I remove the mandrel and fill the tube with melted resin, lead, or other substance which may be found suitable for the 70 purpose—that is to say, for preventing collapse under pressure. Such filled tube X is laid upon the matrix A, across the cavity of the same, as shown in dotted lines, Fig. 6, and then forced into the matrix A by means of the 75 plunger B until the parts assume the position shown in full lines, same figure. The resin or lead filled tube thus receives the required shape without the least irregularity or imperfection in any particular.

In the case of the band made from a seamless tube the latter is formed by puncturing a plate of the required outline and proportions and then gradually drawing out the same into a cylinder, which is passed through drawing-dies until reduced to flat shape, and subsequently manipulated or operated upon in the same manner as the seamed tube.

The plunger B may form part of a drop-press or be operated in any other preferred 90 manner.

Having thus indicated the best manner of preparing the half-band for the operation of the die in which my invention is embodied, I 95 will now describe the die more in detail.

The receiving portion or matrix A consists of three principal parts—to wit, the fixed central or bed piece, a, and the removable side pieces, b b. The piece a is a steel plate having flat parallel sides and the same width as 100 the band or bracelet to be produced, and is preferably formed solid or in one piece with the horizontal base. The edges of the recess in such part a are cut sharp and true, and the

sides *b b*, having perfectly flat and parallel inner sides, form, when clamped against the center piece, *a*, very perfect angles.

The plunger *B* is flat and parallel-sided, and fits closely between the parallel sides *b b* of the receiving-die *A*. When the tube has been forced into the die *A*, and thus received the required shape and regularity and smoothness of angular edges and flat sides, it is held so tightly between the sides *b b* of the die *A* as to render its removal difficult and impracticable without distortion or other injury. Chiefly for this reason the sides *b* of the dies are made removable or separable from the center part, *a*; but when a half-band is to be shaped in the die the sides *b* are held firmly against the central part, *a*, as shown in Fig. 7. The means for effecting this are screws *c*, working in lugs *d*, that form integral portions of the base of the die. Such lugs are arranged one diagonally opposite each corner of part *a*, and the screws bear upon the beveled ends of the sides *b*. After the half-band has been pressed as required the screws *c* are operated to allow separation of one or both of the sides *b* from the center part, *a*, so that the half band or bracelet may be lifted out. The sides *b* are then re-

clamped in their former position, and the die is in readiness for the operation on another flat tube.

In place of making one or both sides of the matrix removable, they may be fixed and the bed-piece *a* made movable instead, so that it may be raised or pushed up to effect the extraction of the half-band.

I do not claim, broadly, a die having one of its sides movable; but

What I claim as new is—

The improved die for manufacture of half-bands of gold bracelets, the same consisting of the matrix formed of the bed-piece *a* and the removable side pieces, *b b*, having beveled outer corners and parallel inner sides, which are in contact with said part *a*, the adjusting and clamping screws *c*, and the plunger *B*, which has a rounded lower edge and parallel vertical sides that adapt it to fit accurately in the cavity of the matrix, all as shown and described, for the purpose specified.

SHUBAEL COTTLER.
